UNITED STATES PATENT OFFICE.

WALTER GEORGE WOLFE, OF WAKEFIELD, MASSACHUSETTS, ASSIGNOR TO FRANK VAN RAALTE, OF BOSTON, MASSACHUSETTS.

TAXIMETER.

1,043,381.

Specification of Letters Patent.

Patented Nov. 5, 1912.

Application filed July 1, 1910. Serial No. 569,868.

To all whom it may concern:

Be it known that I, WALTER GEORGE WOLFE, a citizen of the United States, residing at Wakefield, in the county of Middlesex and State of Massachusetts, have invented certain new and useful Improvements in Taximeters; and I do hereby declare the following to be a full, clear, and exact description of the invention, such as will enable others skilled in the art to which it appertains to make and use the same.

The present invention relates to an improvement in taximeters.

The object of the invention is to produce an improved form of taximeter particularly intended to eliminate fraud by the driver either upon the fare or upon the owner of the vehicle.

Further objects of the invention are pointed out in connection with the description of the taximeter hereinafter set forth.

To the above ends the present invention consists in the taximeter hereinafter described and particularly pointed out in the claims.

In the accompanying drawings illustrating one form of the invention, Figure 1 is a front elevation; Fig. 2 is a plan; Fig. 3 is a sectional elevation taken on the line 3—3 of Fig. 2; Fig. 4 is a right hand end elevation; Fig. 5 is a sectional view on the line 5—5 of Fig. 2, illustrating the printing mechanism for the mileage indicator; Fig. 6 is an end elevation of the counter viewed as seen in Fig. 1; Fig. 7 is a front elevation of the counter viewed from the right, as seen in Fig. 6; Fig. 8 is a sectional elevation on the line 8—8 of Fig. 3, illustrating the mechanism for connecting and disconnecting the counter with a vehicle wheel; Fig. 9 is a sectional elevation on the line 9—9 of Fig. 1; Fig. 10 is a detail of the lower end of the signal lever; and Fig. 11 is a section on line 11—11 of Fig. 10.

In describing the taximeter illustrated in the accompanying drawings, a general description of the whole machine will first be set forth, and then a detailed description of the various parts of the machine will follow.

As the object of the invention is to secure a taximeter upon which the passenger or fare is willing implicitly to rely, and at the same time to secure an instrument which will secure for the vehicle owner the re-

ceipt of all the money collected by the driver, the taximeter contemplates the delivery to the fare of a check whereon is printed the amount of the charge made to him for the service, a duplicate of which is retained in the machine and out of access of the driver, for the use of the owner of the vehicle, hereinafter, for convenience, referred to as the company.

When a fare hires the vehicle the driver takes hold of the signal and turns it ninety degrees to the right, as illustrated in Fig. 1, thereby causing a movement of the counter to indicate the minimum charge and at the same time connecting the mileage indicator with one of the front wheels. With the travel of the vehicle, the counter is actuated to record, in fare equivalents of the distance, the charge to be made to the fare. If now, without discharging the vehicle, the fare suspends travel, as by paying a call, and the vehicle is kept waiting, the charge for the time during which the vehicle is kept waiting is indicated by the driver, in the presence of the fare, by turning the waiting charge indicator to the amount determined by the length of time during which the vehicle was kept waiting. Thereupon, with the journey resumed, the counter records the charge to be made for the distance traveled. At the end of the journey, when the vehicle is discharged, the driver takes hold of the signal and moves the signal from occupied to vacant position, which is the position indicated in Fig. 1. This movement of the signal causes the printing mechanism to take an impression from the counter and waiting wheels of the amounts indicated thereby. It also resets the counter wheels back to zero and disconnects the counter from the vehicle wheel, so that the driver may take the vehicle to his stand again without recording charges. The impression from the mileage and waiting-charge indicators having been made upon the paper, the driver turns the proper crank, which causes the machine to feed through a slot in the cover one of the two pieces of paper upon which the amount so stamped appears. Having fed a sufficient length of this strip through the cover, the driver tears it off and hands it to the fare, who pays the sum of the amounts indicated by the mileage and waiting-charge indicators.

Clutch.—The flexible shaft cover 10 leads

the flexible shaft from the front wheel of the machine to the worm shaft 11, carrying a worm which engages the worm wheel 12 mounted in a bearing 13 and supported on 6 the frame of the machine. The worm wheel carries a striker 14 which engages the counter lever 49, by which the counter is actuated to count the rotations of the worm wheel 12. The worm wheel 11 is mounted in 10 bearings 15 and 16 which are pivotally mounted, the former on the side 17 of an inverted U-shaped frame piece and the latter at 18 on the opposite side 19 of said inverted U-shaped frame piece. The above 15 described arrangement is such that the bearings 15 and 16 may be swung about their pivots on the frame piece 17, 19 so as to throw the worm into and out of mesh with the worm wheel 12. This movement of the 20 worm shaft is accomplished by means of a lever 20 pivoted at 21 to the side 19 of the frame piece, by the engagement of the end 22 of said lever to the under side of the bearing 16. When the lever 22 is turned by de- 25 pressing the long arm, as viewed in Fig. 8, it lifts the worm shaft to throw the worm into mesh with the worm wheel. The longer arm 23 of the lever 20 is engaged by a spring 24 which normally tends to pull such arm down 30 and by the end 25 of the lever 26 pivoted at 27 upon the back piece 28 of the frame of the machine. This lever 26 will, for convenience, be referred to hereafter as the clutch lever. It is adapted to be actuated by an 35 other lever 119 hereafter referred to as the clutch and reset lever. The clutch and reset lever 119 in turn is actuated by a movement of the signal lever 98 in the direction to move it from occupied to vacant position.

40 *Counter.*—The counter comprises the devices for counting the money units corresponding to the distance traveled and the minimum charge. In general, in construction, organization and mode of operation, it 45 conforms to the counter illustrated and described in the patent to Wolfe for counters, No. 1,003,022, patented September 12, 1911. In certain details of construction, however, it departs therefrom. It will suffice, it is thought, to identify various parts of the counter herein illustrated with the corresponding parts of the counter illustrated in said patent. The dime, dollar and eagle wheels are designated 29, 30 and 31 50 respectively, and correspond to the dime, dollar and eagle wheels 5, 6 and 7 of said patent. The wheels are each provided with clock springs for returning them to their zero positions. The wheels are each pro- 55 vided with ten ratchet teeth; the depth of the notches for nine of the teeth is the same, but for the tenth tooth a deep tripping ratchet notch is provided for the purpose of causing a variation in the operation of the pawl 60 mechanism acting to throw the ratchet of

the next higher wheel into engagement with the teeth of the ratchet of the next higher wheel. The dime wheel 29 is provided with a detent, adapted to engage a back-stop mounted on the stop slide 32 carried by the 70 cross-piece at the top of the frame of the counter instead of at the bottom, as in said patent. The ratchet mechanism operates to advance the dime wheel tooth by tooth until it has completed one rotation, when it is released. Then it is propelled by its spring to rotate backwardly until the detent strikes the back-stop. This is all as in the construction of said patent. The dime pawl 33 shown in front elevation in Fig. 7 corre- 75 sponds to the pawl 21 illustrated in said patent. It is pivotally mounted upon the pawl carrier 34, corresponding to the part 22 of said patent. The pawl carrier 34, in turn, is provided at its end with ears pivot- 80 ed at 35 to the arms 36 which in turn are pivoted at 37 to the uprights 38. These correspond to the pawl carrier 22 and arms 34 pivoted at 25 to the uprights 10 in said patent. A cross-bar 39 (corresponding to the cross-bar 26 of said patent) is also pivoted at 35 to the arms 36 and is provided with an ear 40 (corresponding to the ear 27 in said patent) to which at 41 is pivoted the link 42 pivoted at 43 to the uprights 44. Upon the 85 upper surface of the link 42, above the pivot 41, a roller 45 rests, which is pivotally mounted in the arms 46 which are pivotally mounted at their ends at 47 in the uprights 44. The outer end of the arms 46 carries a pin 48 upon 90 which the counter actuating lever 49 bears. The counter lever 49 is pivoted at 50 to the uprights 44. Oscillations of the arm 49 impart 95 precipitations to the pawl carrier 34 which cause the actuation of the ratchet wheels. 100 The above described arrangement is such that with each rotation of the worm wheel 12 the striker 14 causes an oscillation of the pawl-actuating lever 49 which causes the pawl-carrying bar 34 to be moved in the 105 direction to cause the pawl to advance the dime wheel one tooth. The pawl 33 is provided with a tooth-engaging portion which is adapted to engage the several teeth of the ratchet wheel 29. This pawl is also pro- 110 vided with a tooth-engaging portion and also with an incline, corresponding respectively to the tooth-engaging portion 35 and the incline 36 of the construction of said patent. The pawl is pivoted on the pawl-carrier to permit lateral movement, as in 115 said patent, and the same sort of a spring for holding it in normal position is provided. With each actuation of the pawl-carrier, the dime wheel is advanced one-tenth of a rotation until nine teeth have 120 been racked by, then with a return of the pawl to its upper position, it finds itself in the tripping ratchet notch, corresponding to the tripping ratchet notch 16 of said pat- 125 130

ent. Then upon its next advancing movement the pawl falls down into this tripping ratchet notch, a spring attached to the pawl-carrying bar pulling the pawl in the direction to enter said notch. This downward movement of the pawl brings the inclined surface thereof into engagement with the outer inclined side of a tripping prong, corresponding in position and function to the tripping prong 40 of said patent, which swings the pawl laterally against the pressure of its spring out of engagement with the ratchet wheel, thereby, so far as the pawl is concerned, releasing the ratchet wheel. The end of the pawl now bottoms on the releasing lever 51 and swings the left-hand end of that lever downward thereby causing the right-hand end 52 to rise. The ratchet wheel 29 is provided with ten retaining holes adapted to be engaged by a detent 53 mounted in the end of a spring-arm 54 secured at 55 to the frame of the machine. The right-hand end 52 of the releasing lever 51 is provided with a wedge head 56 which, when the releasing lever 51 is oscillated in the manner above described, slides under the detent-carrying arm 54, and lifts it so as to withdraw the detent 53 from the hole corresponding to the retaining hole in the ratchet disk 29. The downward motion of the pawl, therefore, at the time when it enters the tripping ratchet notch, operates to cause the bar to be withdrawn from engagement with the ratchet wheel, in the manner above described, and at the same time to withdraw the detent from engagement with the ratchet wheel, so that the ratchet wheel is entirely released from control by either the retaining means or the pawl, and it then rotates backward under the influence of a clock spring to its original position, thereby bringing the figures on it indicating zero back to the bottom of the roll, the dime wheel then occupying the position illustrated in Fig. 7 and being ready to count another series of ten quarter miles. Each of the releasing levers 51 is provided with a spring 57 normally tending to hold it in raised position, and corresponding in function to the spring 48 of said patent. Springs 58 attached to the cross-bar 39 are provided to lift the pawl-actuating lever and associated parts in the position illustrated in Fig. 6. Each rotation of the dime wheel and its restoration to its original position are accompanied by the advance of the dollar wheel one notch, so that the advance of the dime wheel ten notches and its return to its original position secures the advance of the dollar wheel one notch. This is accomplished as follows:—When the pawl 33 falls into the tripping ratchet notch of the dime wheel, the pawl-carrying bar 34 is permitted to swing downward farther than it does when it engages the other teeth

of the dime ratchet wheel, and this added movement of the pawl-carrying bar 34 suffices to bring the dollar pawl 59 into engagement with the first tooth of the ratchet wheel of the dollar wheel 30, and then with the completion of the forward movement of the pawl-carrying bar 34, the dollar wheel is advanced one tooth from a zero reading to a reading of 1, as the dime wheel is released and restored to its zero position. Only when the pawl 33 enters the tripping ratchet notch of the dime wheel does the pawl 59 engage the teeth of the ratchet wheel of the dollar wheel. Similarly, only when the pawls 33 and 59 engage the tripping ratchet notches of both the dime and dollar wheels, does the eagle pawl 60 engage the teeth of the ratchet wheel of the eagle wheel 31. The depth of the notches in the dime wheel is so slight that except when the pawl 33 enters the tripping ratchet notch thereof, the pawl 59 does not descend low enough to engage the teeth of the ratchet wheel on the dollar wheel. So also with the other wheel, that is, the depth of the notches in the ratchet wheel of the dollar wheel is such as to hold the pawl-carrying bar 34 so high that the pawl 60 cannot engage the teeth of the ratchet wheel of the eagle wheel except when the pawls 33 and 59 enter the tripping ratchet notches of both the dime and dollar wheels. It should be remarked, in passing, that the dime and dollar pawls swing to the right, as viewed in Fig. 7, while the eagle pawl swings to the left. The releasing levers of the dime and dollar wheels are both located on the right-hand sides of the dime and dollar wheels, while the releasing lever for the eagle wheel is located on the left-hand side thereof.

Waiting indication.—The waiting dime wheel 61 and the waiting dollar wheel 62 are mounted, the former in the upright 63 and the latter in the upright 64. Their adjacent surfaces are provided with star recesses, similar to those illustrated in said patent. A loose shaft 65 extends through both the dime and dollar waiting wheels and carries a star wheel 66 adapted to be engaged with either the one or the other thereof, as in said patent. The knurled head 67 secured to the star shaft 65 affords provision for turning the waiting wheels. Ratchet wheels 68 and 69 are provided to prevent backward rotation of these wheels respectively. The driver, after the waiting is concluded, will tell the fare the charge for the waiting, and turn the waiting wheels to the proper position to indicate the charge to be made therefor.

Check paper and printing mechanism.—A double strip of paper, with carbon paper between the two strips, is mounted on the spool 70, and the double strip with the carbon paper between carried in a path indicated

by line 71, first between the feed rollers 72 and 73, of which the former is a steel roll and the latter a rubber roll, thence under the mileage-counter wheels and waiting-time wheels to the take-up spool 74. The strip is divided after reaching the spool 74, and one strip 75 runs outside of the machine while the other, together with the carbon paper, is wound up on the spool 74. Referring to Fig. 5, the strips pass through the space 76, the opening 77 in the plate there being provided to permit the strips to be pressed upward against the wheels of the counter, when the impression is taken therefrom. Fig. 5 illustrates the construction of the printing mechanism for printing the amount indicated by the counter and which consists of a platen 78 mounted upon a vertical stem 79 carried in a sleeve 80 and actuated by a lever 81 pivoted at 82 to the frame of the machine, the opposite end of the lever being pivotally connected with a stud 83 by means of a pin 84 which extends outward in opposite directions from the said stud and engages the lever 81 on the one side and the lever 85 of the printing mechanism for the waiting wheels on the other side. Suitable framework is provided for the parts illustrated in Fig. 5. A spring 86 under the stud 83 normally holds the platen down. The two printing mechanisms, the one for the counter and the other for the waiting wheels are identical in construction. The feed rollers 72 and 73 and the receiving spool 74 are connected by a link-belt 87, the sprocket wheel 88 on the feed roller 73 being secured to the shaft of such roller, while the sprocket wheel 89 of the shaft of the receiving spool 74 is loosely mounted on such shaft, being journaled in the stand 90 and frictionally connected with the receiving spool 74 by means of a friction clutch contrivance consisting of a star spring 91 which is secured to the sprocket wheel 89 and adapted to bear with frictional pressure upon the side of the receiving spool 74. The supply spool 70 is provided with a similar star spring to hold it from overrunning. A crank 92 is provided for advancing the check strips. The check strip 75 which emerges through a hole in the cover of the machine is to be torn off and handed to the fare, while the duplicate thereof is to be wound up upon the receiving spool 74.

55 *Interconnecting devices.*—Starting with the vehicle waiting for a fare, with the signal in the position indicated in Fig. 1, that is, the vacant position, the driver throws the signal down to the occupied position. This operates to cause the counting of the minimum fare and to close the clutch connection with the vehicle wheel. The signal staff 93 is provided with a by-pass pawl 94 pivoted at 95 to the staff 93, and provided with a spring 96 to return it to the

position illustrated in Fig. 10. This by-pass pawl may be called the minimum-fare pawl, as it engages the horn 97 of the lever 98 pivoted at 99 to depress the same and thereby cause its end 100 to engage the end 101 of the cross-lever 102 pivoted at 103, the opposite end 104 of which engages the end 105 of the lever 106 pivoted at 107, the opposite end 108 of which is provided with a pin 109 secured in the vertical rod 110 supported in a bar 111 secured to the frame of the machine, and normally held in raised position by the spring 112. The upper end of the rod 110 carries the counter-lever engaging arm 113 which engages the end 114 of the counter-lever 49. The above described arrangement is such that when the signal is thrown from the vacant position illustrated in Fig. 1 to the occupied position at right angles thereto, the minimum-fare pawl 94 operates to cause a quarter mile actuation of the counter, to thereby cause it to register the minimum fare. The lever 98 through the cross-lever 102 actuates the lever 106 to cause the rod 110 to be depressed, so that its end 113 shall cause the movement of the counter-lever 49. Upon the movement of the signal lever to the vacant position, the minimum-fare pawl 94, being pivotally mounted on the staff 93, passes the horn 97 without operation thereof. A spring 115 attached to the end 105 of the lever 106 normally tends to hold the parts in position with the end 113 raised to the top of its backward movement. A spring 116 holds the end 100 of the lever 98 down on the end 101 of the cross-lever 102. The same movement of the signal from the vacant to the occupied position carries the roller 117 mounted on the staff of the signal lever from the position illustrated in Figs. 1 and 3 downward to the right. The staff 93 is pivoted at 118 upon a part of the frame of the machine, and the curvature of the surface of the clutch-and-reset lever 119 is such that this movement of the roller 117 permits the lever 119 to rise. The clutch-and-reset lever 119 bears upon its rear side the boss 120 which rests upon the end 121 of the clutch lever 26, so, therefore, when the clutch-and-reset lever 119 rises, it permits the end 121 of the lever 26 to be raised through the medium of the spring 24 which pulls down the end 23 of the lever 20 resting upon the end 25 of the lever 26, the opposite end 22 of the lever 20 at the same time raising the worm into engagement with the worm wheel 12, thereby closing the clutch and connecting the striker-actuating mechanism with the vehicle wheel. Thus it is seen that when the signal is moved from the vacant to the occupied position, it operates to cause the registration of the minimum fare and to clutch the counter to the vehicle wheel. The movement of the signal in the

opposite direction, from the occupied to the vacant position, does two things. First, the roller 117, by engagement with the clutch-and-reset lever 119, causes the opening of the clutch, and therefore, the disconnection of the counter from the vehicle wheel. In passing, it may be observed that this movement of the signal has no effect upon the minimum fare connections. This movement of the signal lever from the occupied to the vacant position also prints the fare and resets the counter. The actuation of the printing devices is secured by means of the printing pawl 122 pivotally mounted on the lower end of the staff 93 of the signal lever. This pawl is a by-pass pawl, being provided with a spring 123 normally holding it in the position illustrated in Fig. 10, but permitting it to swing to the right, as viewed in said figure, during the movement of the signal from the vacant to the occupied position, so that no actuation of the printing mechanism occurs at this time. This printing pawl 122, when the signal is thrown from vacant to occupied position, passes by the horn 124 of the printing lever 125 pivoted at 126 to the frame of the machine, so that during the time the vehicle is occupied the pawl 122 rests upon the upper surface 127 of the horn 124. The lever 125 bears upon the pin 128 secured in the stud 83 of the printing mechanism. The above described arrangement is such that when the signal is thrown from occupied to vacant position the pawl 122 engages the surface 127 of the horn 124 of the printing lever 125 and swings such lever downward, causing it to depress the pin 128 connected with the stud 83, whereby the platens of the printing devices are raised and an impression from the wheels of the counter and the waiting wheels is made upon the check strips.

Passing now to the resetting of the counter, which is an operation required to be performed after the printing of the amount indicated thereby. The clutch-and-reset lever 119 bears upon its front side the boss 129 (Figs. 2 and 3) which is connected with the resetting devices for the counter. This boss 129 engages the projection 130 (Fig. 3) of the reset slide 131 which is slotted at 132 (Fig. 1) and secured by screws 133 to the standard 134 rising from the base of the machine. A spring 135 (Fig. 1) secured to the standard 134 at 136 extends downward and is secured at its lower end to the slide 131 which it thereby normally tends to hold in raised position. The upper end of the slide 131 is provided with a table 137 (Fig. 4) which engages a pin 138 (Fig. 4) which is connected to the vertical slide 139 at one end and to the vertical slide 140 at the other end. The slide 140 is slotted at 141 (Fig. 4) and slidably secured to a part of the frame of the machine 142 by means of the

screws 143. The slide 140 communicates motion to the pawl carrier 34 for the purpose of lifting the same, and the slide 139 communicates motion to the releasing lever 51 for the purpose of releasing the counter 70 wheels. The lower end of the slide 140 is provided with a projection 144 (Figs. 2 and 7) which engages one end of the lever 145 pivoted at 146 (Fig. 2) on a portion of the frame of the machine. The other end of the lever 145 engages a slot in the vertical slide pin 147 (Fig. 7) supported in the bar 148 to the frame of the machine and which engages at its upper end the left-hand end of the pawl carrier 34 (Fig. 7), thereby acting, when it rises, to raise the pawl carrier and disengage the pawls from the ratchet wheels of the several counter wheels. The slide 139 is slotted at 149 (Fig. 1) and secured by screws passing through such slots 80 to a portion of the frame of the machine, and it bears at its lower end against the left-hand end, as viewed in Fig. 7, of the release-controlling lever 150 (Fig. 6) pivoted at opposite sides of the frame of the machine, 90 at the right-hand end at 151 (Fig. 6) and at the left-hand end at a similar place on the opposite side. This release-controlling lever 150 has a lip 152 (Figs. 6 and 7) which engages the ends of the releasing levers, so 95 that when the release-controlling lever 150 is depressed, its lip 152 engages the ends of the releasing levers 51 for the dime wheel, 153 for the dollar wheel and 154 for the eagle wheel, so as thereby to release all of 100 these wheels and permit their return to zero. A spring 155 (Figs. 6 and 7) secured at one end to the frame of the machine and at the other end to the release-controlling lever 150 normally tends to support that lever in 105 its raised position.

To revert to the movement of the signal from occupied to vacant position, we observe now that such movement first causes the printing mechanism to stamp the amounts indicated by the counter and waiting wheels upon the check strips and then releases the counter wheels by the lifting of the pawls and the raising of the detents from engagement with the holes in the counter wheels. 110

The operation of the machine has been described in connection with the description of the various parts thereof, and it is deemed unnecessary here to repeat such operation. 115

It is to be understood that this machine is to be inclosed in a suitable casing or shell so as to prevent the access of the driver thereto. It is also to be understood that while the embodiment illustrated in the drawings is that which the applicant has produced and which performs the operation hereinbefore described, and is, therefore, the best embodiment which the applicant has yet made, his invention is not limited to 125 130

such specific embodiment as it may be embodied in other and different forms within the contemplation of the invention defined in the claims.

5 While in the foregoing specification the counter has been referred to by that name alone, it is to be understood that such counter is intended to make an indication in money of the distance which the vehicle 10 has carried the fare, so, therefore, in some of the claims the counter has been referred to as a mileage indicator. Similarly, the wheels which indicate the charge for the time during which the machine is kept waiting, may conveniently be referred to as the 15 waiting charge indicator.

Having thus described the invention, what is claimed is:—

1. A taximeter, having, in combination, a 20 counter, a signal formed by a pivoted arm, means for connecting the counter to a vehicle wheel, minimum charge devices, a lever for operating the said minimum charge devices, and a pawl on the signal arm 25 adapted to engage said lever when the arm is thrown from vacant to occupied position and cause said counter to register the minimum charge.

2. A taximeter, having, in combination, 30 counting wheels, holding means and actuating means for the counting wheels, a signal formed by a pivoted arm, means for operating the counter actuating means from a vehicle wheel, means operated by the signal 35 when moved from vacant to occupied position to actuate the counting wheels and register the minimum charge, means for guiding a record strip beneath the counting wheels, a platen, a pawl carried by the signal, and a lever connected to the platen and 40 adapted to be moved by the pawl when the signal is thrown from occupied to vacant position to press the strip into contact with the counting wheels.

45 3. A taximeter, having, in combination, counting wheels, holding means and actuating means for the counting wheels, a signal, means for operating the counter actuating means from a vehicle wheel, means 50 operated by the signal when moved from vacant to occupied position to actuate the counting wheels and register the minimum charge, a pair of rolls adapted to carry a record strip, means connecting said rolls together whereby the record strip will be wound from one roll to the other, means for 55 guiding the record strip beneath the counting wheels, a platen, a lever connected to the platen, and means carried by the signal 60 adapted to engage the lever when the signal is thrown from occupied to vacant position to operate the platen.

4. A taximeter, having, in combination, 65 counting wheels, actuating means for the counting wheels, a signal for indicating

whether the vehicle is occupied or vacant, means for operating the counter actuating means from a vehicle wheel, means operated by the movement of the signal from vacant to occupied position for turning the counting wheels to register a minimum charge, and means acting automatically for returning the counting wheels to zero position when the signal is thrown from occupied to vacant position.

5. A taximeter, having, in combination, 70 counting mechanism, an actuating lever connected thereto, means for turning the lever to actuate the counting mechanism from a vehicle wheel including a wheel having a 75 striker adapted to contact with said lever, and means adapted to contact with and turn the lever independently of said striker for registering the minimum charge on the counting mechanism.

6. A taximeter, having, in combination, 80 counting wheels, means for actuating the counting wheels from a vehicle wheel including a clutch, means for resetting the counting wheels to zero, a signal lever for 85 indicating whether the vehicle is occupied or vacant, a clutch-and-reset-lever adapted to be turned when the signal lever is turned from occupied to vacant position, connections between the clutch-and-reset-lever and the clutch acting to disengage the clutch when the signal lever is thrown from occupied to vacant position, and connections between the clutch-and-reset-lever and the resetting means acting to allow the resetting 90 means to turn the counting wheels to zero when the signal lever is thrown from occupied to vacant position.

7. A taximeter, having, in combination, 95 counting wheels, actuating means for the counting wheels, means for operating the counter actuating means from a vehicle wheel, a signal lever for indicating whether the vehicle is occupied or vacant, means for 100 guiding a record strip beneath the counting wheels, a platen, a pawl carried by the signal lever, a lever connected to the platen and adapted to be moved by the pawl when the signal lever is thrown from occupied to 105 vacant position to press the strip into contact with the counting wheels, means for resetting the counting wheels to zero, a lever connected to said resetting means and having a cam surface adapted to be engaged by the signal lever so as to actuate the resetting 110 means after the platen has pressed the strip against the counting wheels.

8. A taximeter having, in combination, a 115 counting wheel, mechanism for turning the counting wheel, means including a clutch for actuating the counting wheel turning mechanism from a vehicle wheel to register a mileage charge, a signal lever for indicating whether the vehicle is occupied or vacant, means including a pawl and ratchet 120

connection with the signal lever for actuating the counting wheel turning mechanism to register a minimum charge when the signal lever is moved from vacant to occupied 5 position, means including a pawl and ratchet connection with the signal lever for making a printed record of the charge indicated by the counting wheel, holding and resetting means for the counting wheel, and mechanism 10 including a clutch-and-reset-lever actuated by movement of the signal lever from occupied to vacant position for disengaging the clutch and for releasing the holding means and allowing the counting wheel to 15 be turned to zero by the resetting means.

9. A taximeter, having, in combination, counting wheels, actuating means for the counting wheels, a clutch for connecting said counting wheels to a vehicle wheel, a 20 spring normally tending to hold said clutch engaged, holding means for the counting wheels, a spring normally holding said holding means in engagement with the counting wheels, mechanism for taking a printed record 25 from the counting wheels, mechanism for turning the counting wheels to indicate a minimum charge, a signal for indicating whether the vehicle is occupied or vacant, connecting means between the signal and the printing mechanism including a pawl adapted 30 to actuate the printing mechanism when the signal is thrown from occupied to vacant position, connecting means between the signal and the minimum charge mechanism in-

cluding a pawl adapted to actuate the minimum charge mechanism when the signal is thrown from vacant to occupied position, and means adapted to disengage the clutch and counting wheel holding means when the signal is thrown from vacant to occupied 40 position and to hold said clutch and holding means in disengaged position while the signal is in occupied position.

10. A taximeter, having, in combination, counting wheels, means for actuating the counting wheels from a vehicle wheel, a waiting charge indicator wheel, means for operating the waiting charge indicator wheel to indicate the amount of such waiting charge, two platens adapted to coöperate 50 with the counting wheel and the waiting charge wheel respectively, means for guiding a record strip over both platens, a spring for each platen acting to withdraw the platens from their respective wheels, levers connected to the platens, a signal lever for indicating whether the vehicle is occupied or vacant, and connections between the platen levers and the signal lever acting to move the platens to press the strip into contact 55 with the counting and waiting charge wheels when the signal lever is thrown from occupied to vacant position..

WALTER GEORGE WOLFE.
